UNITED STATES PATENT OFFICE.

JOHN B. LIGHTON, OF SYRACUSE, NEW YORK.

DESIGN FOR A CASE FOR COIN-OPERATED MACHINES.

SPECIFICATION forming part of **Design No. 22,080**, dated December 20, 1892.

Application filed November 11, 1892. Serial No. 451,690. Term of patent 7 years.

To all whom it may concern:

Be it known that I, JOHN B. LIGHTON, a citizen of the United States, residing at Syracuse, in the county of Onondaga and State of New York, have invented and produced a new and original Design for a Case for Coin-Operated Machines, of which the following is a specification, reference being had to the accompanying drawing, showing a part thereof.

10 The annexed drawing presents a perspective view of a coin operated machine case embodying my design.

The leading feature of my design consists in the upright rectangular body (A) which rises from a sloping or beveled base as shown. From the center of the top of the body rises the head (A'), leaving shoulders (a—a) at op-

posite sides of the base of the head. The body (A) has a cup-shaped projection (b), and is embellished at its front by a central panel (c) which is surrounded by ornamental embossments represented in the form of radial ribs (d—d), and over said panel is a second panel (e), over which is an ornamental representation of a disk (f) with vines extending therefrom as shown.

What I claim is:

The design for a case for coin-operated machine, as shown.

JOHN B. LIGHTON.

Witnesses:

H. M. SEAMANS,
C. L. BENDIXON.
